pany, Central Falls, R. I., a corporation of
Massachusetts

Application August 1, 1942, Serial No. 453,260

1 Claim. (Cl. 66—1)

The subject matter of this case is an invention relating to knitted hosiery and method of producing the same. More specifically, the invention deals with the physical construction of a hosiery top for purposes of making an anklet and the method of knitting and finishing that top.

Anklets have been knitted in which the tops have been of plain knitted type, but those tops have, in practically all instances of which we are aware, been rendered self-sustaining by incorporation of elastic yarn in some manner. The elastic yarn has been incorporated under tension and serves to hold the top of the anklet tightly about the ankle, also retains the anklet itself in position preventing the top from falling down and creating an unsightly and wrinkled appearance. The same has been done with regard to true rib tops although in some instances true rib topped anklets are made without incorporation of elastic yarn.

According to the present invention an anklet top is knitted having no elastic yarn incorporated therein but having enough contraction and tendency to remain in contracted state so that it will fit the ankle of the wearer tightly, also will remain in position if the anklet is made of appropriate length.

The construction of an anklet top of this type upon a single bank of needles makes it unnecessary to resort to rib type machines thus avoiding transfer operations or costly and complicated mechanisms such as automatic type true rib machines in which a true rib top is first knitted and then transfer made to cylinder knitting or plain knitting for finishing the leg and foot of the stocking. Since knitting is on a single bank of needles, it is much easier to knit string work and thereby render the machine operation practically automatic in all respects.

In knitting the fabric of the top itself, two feeding stations are preferably employed, one being designated as the main or usual knitting station of this type of machine and the other being an auxiliary station at which a single yarn may be fed to selected needles. At the said auxiliary station every other or appropriate selected needles are raised and take the auxiliary yarn in their hooks, draw it into a stitch and cast off the previously held loop or loops. This auxiliary yarn may be a yarn finer in diameter than the yarn feeding at the so-called main station at that time, according to the better practice, but that is not absolutely essential. At the main

5 side of the machine and during knitting of the top portion, a so-called main yarn is fed and will be taken and knitted by all needles employed in the production of the stocking top. The resulting fabric is of accordian type and will have a ribbed appearance since the auxiliary yarn which floats behind intermediate wales draws the alternate wales laterally together projecting the said intermediate wales to the face of the fabric.

10 The top may be started with a selvage or not depending upon later handling, that is, depending upon whether or not a selvage is desired merely for purposes of handling the knitted articles during subsequent operations. If a selvage is desired it may be formed in any known way, 15 preferably by knitting on every other needle and thereafter on every needle and casting off the first course. The fabric for the top is knitted about twice as long as the ultimate top construction desired and is subsequently turned inwardly and sewed on any satisfactory type sewing machine and by using any of the well-known stitches for the purpose. In sewing it is only essential that the seam have sufficient elasticity to allow 20 the top to stretch at that particular point sufficiently for putting it on over the heel.

25 The tops are, however, finished before the sewing operation is done. This finishing operation constitutes a drawing out of fabric lengthwise and forming it to proper diameter and is accomplished by the usual wetting, steaming and boarding under heat. After the articles are removed 30 from the board, they may be sewed at any convenient time. Since the boarding is done while the top is of a single thickness, finishing of the entire stocking is evenly distributed and it is not found necessary to employ greater heat at any one point than at another. This obviates any 35 tendency to burn thinner sections as frequently happens if an article is finished which has parts of single and other parts of double thickness. The other extreme is also avoided, that is, to 40 avoid burning the thinner sections, it is not necessary to discontinue finishing the top before the same is dry and has been sufficiently set.

45 Detailed description of the fabric and of one preferred manner in which the same is knitted will be described by referring to the accompanying 50 fingers of the drawings in which:

Fig. 1 is a view of part of a stocking knitted in accordance with the invention;

Fig. 2 is a conventional view showing to a greatly enlarged scale the construction of the fabric;

Fig. 3 is an isometric view wherein the method of knitting is illustrated; and

Fig. 4 is a diagrammatic view showing two yarn feeding stations and the pathways of needle hooks as they pass those stations, take yarn and draw that yarn into knitted stitches.

Referring to Fig. 2, the fabric for the stocking top is knitted of two yarns, one yarn indicated by numeral 1 being the heavier and being fed at the main side of the machine. The lighter yarn 2 is fed at the so-called auxiliary feeding point and is sometimes termed the accordion yarn. The fabric as here illustrated is merely a fragment cut from the top and has alternate wales 4, 6 and 8 and intermediate wales 3, 5, 7 and 9. The yarn 2 is drawn into knitted stitches at the alternate wales only, floating over the intermediate ones. The yarn 1 is drawn into knitted stitches at each wale, but in the intermediate wales it is to be noted that there are only loops of yarn 1 while in the alternate wales there are alternating loops of first one yarn and then the other. A certain amount of stitch robbing takes place so that the ultimate length of each of the wales is the same, thus stitches in intermediate wales are much longer than stitches in alternate wales. Depending upon the length of stitch drawn and upon the tension in the yarns and other features, the fabric will be drawn together laterally so that a ribbed appearance is realized.

While a 1 x 1 type rib has been shown by way of example, spacing such as 2 x 1, and others may be employed. No selvage has been illustrated in this fragment of the fabric, but a selvage may be formed as above explained, the fabric may be provided with a small outturned welt at the beginning of each new top, or it may merely be left with a non-selvaged edge as subsequent sewing will lock the fabric against running. However, during the finishing operation it is likely that runs may start so a selvage is preferably provided.

In knitting in string work the articles may be separated by pull courses or by breaking courses and the use of a true selvage makes it easier to separate the individual stockings without damaging the fabric.

In Fig. 1 a stocking having a leg 10 and a top generally indicated at 11 has that top 11 knitted of such length that it may be folded inwardly providing an outer thickness 12 and an inner one 13. The edge of the turned part of the top is sewed on any convenient type of sewing machine and the seam 14 does not show from the outside of the fabric. The welt thus formed will have a ribbed appearance both inside and outside. The seam must be loose or elastic enough so that stretching the top as when putting the same on over the heel is not limited by tightness in the seam itself.

In Fig. 3 several needles and sinkers have been illustrated at and adjacent the auxiliary stitch drawing point. The auxiliary yarn 2 is shown feeding through a convenient feeding finger 15 and alternate needles 16 are raised to take that yarn in their hooks while intermediate needles 17 are not so raised. Needles 18 only have their latches cleared.

Sinkers are of two types, one having the usual rounded nibs 18 while the other group of sinkers has nibs 19 with inclined edges over which yarn 70 may be measured. The sinkers 18 and 19 are alternating as shown in Fig. 3, that is, if a 1 x 1 arrangement is desired. The sinkers having nibs 18 have short butts 20 while the regular sinkers or those having rounded nibs 18, have long butts 75

21. As the said sinkers approach the stitch drawing point at this auxiliary side, regular sinkers are drawn outwardly to a greater extent than the inclined nibbed sinkers, the latter remaining at such a position that the yarn 2 will be measured over the said inclined edges of those sinker nibs. The yarn is shown being measured in that way at the left hand end of Fig. 3, and at the casting off point, all sinkers will be pushed inwardly by the usual casting off cam. Sinkers having nibs 18 serve to do the casting off and hold the fabric in their throats while sinkers having nibs 19 and which are likewise pushed inwardly merely extend the sinker loops or floats of the auxiliary yarn elongating them and imparting to the fabric a certain degree of elasticity and extensibility which it would not otherwise have.

In certain instances the sinkers with inclined nibs may follow the needles which take the yarn 2 rather than preceding them as illustrated herein. The arrangement illustrated is preferred. In certain types of machines it may be desirable for other reasons to measure the yarn over sinkers having nibs of different type, or it may be that the yarn will not be measured over nibs of sinkers at all. Special instrumentalities may be employed for the purpose and in that event, all of these arrangements are contemplated as falling within the scope of the invention herein disclosed.

30 Tension on the yarn 2 is varied in accordance with the length of stitch being drawn and in accordance with other factors such as the weight of the yarn 2, especially as compared to the so-called main yarn 1, and depending upon the gage 35 of the machine and the desired width of the top as it comes from the machine.

Now referring to Fig. 4 the auxiliary feed is generally indicated at A and the auxiliary yarn feeding lever 16 is shown in position to feed yarn

40 2. Needle hooks approach in a pathway 22 and those needles which are selected to take the yarn 2 in their hooks will be raised to an elevated pathway 23 in which they will engage that yarn while the intermediate needles continue at elevation 22 and instead of taking yarn 2 in their hooks engage that yarn behind the hooks and in back of needle shanks. All needles move down to a stitch drawing point 24 as needle butts are engaged by a suitable stitch drawing cam movable to and from active position as desired. Thereafter all needles are raised so that their hooks move along at the elevation 22, then upon approaching the main feeding station M, they will be raised until the elevation 25 is reached, that being an elevation at which needle latches will be cleared. Thereafter all needles take and knit yarn 1 which is feeding through a suitable yarn feeding lever or finger 26, that being one of the usual plurality of such fingers at the main mouth-piece of a machine of this type. In knitting this yarn 1 all needle hooks are drawn down to a stitch drawing point 27 and, of course, sinkers are moved out at appropriate times, inwardly for holding down the fabric, and for casting off the previously drawn stitches, all as is usually accomplished at a feeding and stitch drawing point in hosiery machines. Thereafter the elevation 22 is reached and the cycle is repeated.

By knitting a stocking top as herein described a ribbed appearance is attained and elasticity and contraction are such that as the fabric is finished and later turned inwardly and welted or sewed, the resulting top structure serves very effectively for anklets. The length of the top 11 may be varied as desired for different types of

anklets, but preferably it will be of approximately the proportions shown in Fig. 1 and the leg portion 10 is to be of such length that the top 11 comes at the smallest portion of the ankle.

The fabric is preferably made on a circular, independent needle type machine and, of course, may be produced on any other type machine found convenient for the purpose. In Fig. 3 the line of needles and sinkers is shown straight rather than in the arc of a circle as would normally be the case. That is merely for convenience of illustration.

After the fabric is taken from the machine, whether knitted in string work or separately as by running on or dropping off individual stockings, it is subjected to a finishing operation such as wetting or steaming and then boarding on a heated form. The top itself is elongated on this form and will be narrowed down as desired. After the boarding operation and when the stockings are thoroughly dry, the tops may be welted or sewed at any convenient time.

By finishing before sewing the boarding operation is more easily and satisfactorily carried out. The sewing may be on any convenient type of sewing machine for the purpose. Preferably a sewing machine of Merrow type is used and the seam is generally known as a blind stitch.

If desired, a picot or folding line may be made at the proper place. That will make folding and welting easier and improve the ornamental effect at the edge.

5 The invention has been described by reference to specific details and disclosure of one particular embodiment of the same. It is to be understood that this disclosure is illustrative and refers to a preferred embodiment only and that the invention is not limited otherwise than by the scope of the appended claim.

We claim:

A method of making a stocking top including the steps of knitting one yarn by drawing it into knitted stitches over the throats of the sinkers at each wale in alternate courses of the fabric and knitting a second smaller yarn by drawing it into knitted stitches at alternate wales in intermediate wales in such a way that the sinker loops are looser than the corresponding sinker loops of the other yarn and then turning the fabric inwardly and sewing the upper edge to the lower edge to form a turned or double welt having a ribbed appearance both on the inside and outside.
